UNITED STATES PATENT OFFICE

REGINALD TAYLOR AND FRANK EDGAR COMYN, OF LIVERPOOL, ENGLAND, ASSIGNORS TO ASSOCIATED TELEPHONE AND TELEGRAPH COMPANY, OF CHICAGO, ILLINOIS, A CORPORATION OF DELAWARE

TELEPHONE SYSTEM

Application filed October 13, 1930, Serial No. 488,231, and in Great Britain October 17, 1929.

The present invention relates to telephone systems and is more particularly concerned with automatic systems employing finder switches for connecting a calling party's line with a first numerical switch. Finder switches of the two-directional type adapted to hunt freely in both directions of motion have hitherto been provided individually with certain relays which are only employed when the switch is being set and serve no useful purpose during conversation. It will be appreciated therefore that if the relays which are used for controlling the setting of the switch could be arranged common to a plurality of switches then a considerable saving would result since fewer controlling relays would serve a group of switches than if each switch were equipped with its own individual controlling relays. It is the object of the present invention to produce an arrangement of this character in which switches of the backwardly hunting type are controlled by a set of common controlling relays associated with them during the setting operation over the wipers of a hunting switch.

According to one feature of the invention in a telephone system having finder switches adapted to hunt freely in two directions of motion a relay controlling the hunting operations is adapted to be temporarily associated with any one of a plurality of said finders.

According to another feature of the invention in a telephone system having finder switches each provided with two magnets and adapted to hunt freely in two directions of motion, a relay adapted to transfer the operating circuit from one magnet to the other is adapted to be temporarily associated with any one of a plurality of said finders. The invention will be better understood from the following description of two methods of carrying it into effect, reference being had to the accompanying drawings. It will be understood, however, that this is given by way of example only and that various modifications may be made in the circuit details by those skilled in the art without departing from the spirit of the invention.

Referring now to the accompanying drawings, Fig. 1 shows a finder switch having ac-

cess to one hundred lines while Fig. 2 shows a finder switch having access to two hundred lines in which differentiation between an upper and a lower set of wipers is effected during the hunting motion of the switch. In the case of both figures it must be mentioned that the vertical bank marking arrangement and the subscribers' line relays and substation circuits are not shown in detail but may be similar to that shown and described in the Lomax and Saunders Patent No. 1,688,588 granted 23rd October, 1928, while the emergency change-over arrangements there shown are also contemplated.

Referring now to Fig. 1, when a subscriber served by this finder originated a call, his line relay (not shown) operates and connects earth to the vertical bank contact VB in order to mark the calling level, and at the same time causes relay A to operate in series with resistance 10. Relay A in operating its armature *a*1 extends earth by way of armature *kr*1, winding of relay K, interrupter springs *dm*, winding of driving magnet DM of the finder allotter FA to battery. Relay K thereupon operates over the circuit described and at armature *k*1 extends earth via the resting contacts of armatures *c*1 and *fr*1 by way of wiper 11 and bank contact of the finder allotter, resting contacts of armature *k*3, negative conductor to battery via one winding of the relay (not shown) of the associated group selector. The line relay operates and completes a circuit for the release relay which in turn operates and connects back earth over the release trunk conductor. At armature *k*2 a point is opened in the hunting circuit of the driving magnet DM, and at armature *k*4 earth is connected via the winding of relay C, resting contacts of armatures *kr*2 and *fr*4, wiper 16 and bank contact, vertical magnet interrupter springs V, rotary magnet interrupter springs R, bank contact and wiper 15, armature *k*3, winding of relay G to battery. Relays C and G operate in this circuit, at armature *c*2 a shunt is placed across armatures *kr*2 and *fr*4, and at armature *c*1 the short-circuit across the winding of relay FR is opened whereupon the relay operates in series with the winding of the line relay of the group

selector previously mentioned. When relay FR operates, a circuit is prepared at armature fr_1 for relay KR, at armature fr_2 a shunt is placed across armature kr_1 , at armature fr_3 a circuit is completed for the vertical magnet VM, and at armature fr_4 the original energizing circuit of relay C is opened. It must be mentioned that the armature c_1 is adjusted to break last so as to ensure the locking circuit of relay C being made at armature c_2 before relay FR operates.

The circuit to the vertical magnet may be traced as follows: earth, armature fr_3 , armature g_1 , armature c_3 , and its front contact, 15 wiper 14 and bank contact, rotary off-normal springs RN, winding of vertical magnet VM to battery. Magnet VM will accordingly operate to raise the shaft and wipers the first step, at the conclusion of which the off-normal springs N1 and N2 operate and the vertical magnet V will then, at interrupter springs V, open the circuit of relays C and G. Relay C is slow-to-release and maintains armature c_2 operated but relay G releases and 20 opens the circuit of the vertical magnet at armature g_1 . Continued inter-action between the magnet and relay G will therefore cause the shaft and wipers to be raised to the marked level, whereat the vertical wiper VW will encounter earth on the corresponding vertical bank contact; it will be noticed that relay G is then held operated over the vertical bank in a circuit which does not include the springs V. Relay C it must be mentioned is held operated during the vertical stepping operation on account of the copper slug surrounding its core. When the marked level is found, however, the winding of relay C is maintained 25 opened and the relay therefore releases, at armature c_1 connects earth to the right-hand terminal of relay KR, at armature c_2 opens a point in its own circuit and at armature c_3 the stepping circuit is transferred from the vertical magnet by way of the wiper 13 and 30 bank contact to the rotary magnet RM. The rotary magnet energizes to advance the wipers one step into engagement with the first set of bank contacts in the level chosen, whereupon the rotary off-normal springs RN are operated to disconnect the circuit of the vertical magnet VM, and prepare a circuit to the switching relay H. It must be mentioned that when the rotary wipers make their initial 35 rotary movement the vertical wiper VW disengages the vertical bank contact and until the rotary magnet springs R become operated at the conclusion of the rotary step, relay G is held operated from earth by way of earth over armatures c_2 , g_2 and fr_5 . Relay G releases at the end of the first step, at armature g_1 opens the circuit of the rotary magnet RM, at armature g_2 opens a point in its holding circuit and at armature g_3 removes the short circuit from relay KR whereupon this 40 relay operates from earth via armature c_1 to

battery in series with resistance 17. Relay KR in operating prepares a further point in the circuit to relay H at armature kr_3 , opens the initial energizing circuit of relay K at armature kr_1 , and at armature kr_2 opens a further point in the initial circuit of relay C. If now the contacts engaged by the wipers are not those marked by the operation of the line relay of the calling subscriber, wiper P will encounter earth and a circuit will again 45 be completed for relay G by way of armature h_2 , interrupter springs R, bank contact and wiper 15, armature h_3 , winding of relay G to battery, whereupon the relay will operate and again at armature g_1 complete the circuit to the rotary magnet RM to cause the wipers to be accordingly moved onto the next set of bank contacts. This cycle of operations will 50 continue until the marked line indicated by absence of earth potential is reached whereupon the short-circuit to the switching relay H is removed and the relay then operates from earth at armature kr_3 , wiper 14 and bank contact, operated springs RN, winding of relay H, springs R, bank contact and wiper 15, armature h_3 winding of relay G to battery. It 55 must be mentioned that the latter relay does not operate in this circuit due to the high resistance of relay H.

Relay H in operating completes a locking circuit from earth over conductor P', armature h_1 , winding of relay H, armature h_5 , winding of vertical magnet VM to battery; at armatures h_3 and h_4 connects the negative and positive leads from the group selector through to the wipers of the finder, armature h_3 also disconnects relay FR, and at armature h_2 connects earth fed over conductor P' through to the test wiper P in order to mark the calling line busy and to effect the operation of the cut-off relay in the calling subscriber's line circuit thereby clearing the calling line of its normal battery and earth connections.

The calling subscriber's line relay releases 60 and the marking earth on the vertical bank is removed so that relay A will release unless other lines are calling. Due to the release of relay FR the circuit of relay KR is opened at armature fr_1 and of relay K at armature fr_2 whereupon these relays release. Relay K upon releasing connects earth to its right-hand terminal over armature h_2 . When relay K releases a circuit may be traced from earth at the operated springs N2, bank contact and wiper 12, armature h_2 , interrupter springs and winding of driving magnet DM to battery. Accordingly the wipers of the finder allotter are advanced one step in the search for the next idle finder switch; it will be seen that relay K cannot again operate until such an idle finder is found, owing to the earth connected to its right-hand terminal over off-normal springs of busy finders. Upon the release of the connection at the end 65

of the conversation earth is removed from the release trunk conductor thus causing relay H to release, and a circuit is completed to the group selector release magnet and the finder release magnet ZM from earth over conductor Z, operated springs N1, winding of finder switch release magnet ZM to battery. Hence it will be appreciated that the release of the group selector and the release of the finder switch take place simultaneously.

Referring now more particularly to Fig. 2, this shows a switch similar to that already described but equipped with two sets of wipers arranged to establish connection with 150 subscribers' lines. It will be noticed that in this case the interrupter relay G is of the well-known shunt field type. When a subscriber initiates a call, relays A and K are operated as previously explained whereupon 200 relay C is then operated in a circuit including the right-hand winding of the shunt field relay G. Relay C in operating completes similar functions to those hitherto, and in addition connects earth to the left-hand winding of relay G thereby causing the relay to operate, and at armature g1 to extend earth by way of armature e3, wiper 14 and bank contact, springs RN to the vertical magnet which operates thereby causing the shaft and 250 wipers to be raised one step. At the conclusion of the first vertical step the springs V will then operate and open the circuit of the right winding of relay G which will thereupon release and in turn open the circuit of the vertical magnet VM.

It will thus be appreciated that interaction between relay G and the vertical magnet will result in the shaft and wipers being raised to the marked level whereat the vertical wiper VW will encounter earth on the marked bank contact thereby causing relay G to be held operated even though its original circuit via the winding of relay C is opened at springs V. Relay C will now release since 400 its circuit is opened at springs V and at armature e3 the stepping circuit is transferred to the rotary magnet R. Accordingly the rotary magnet energizes to advance the wipers into engagement with the first set of bank contacts in the level chosen, whereupon 450 the rotary off-normal springs RN are operated in order to prepare the switching circuit of relays HA and HB.

It will be noticed that upon the release of 500 rotary relay C, relay G is held operated from earth connected up by its armatures g2 and g4. At the conclusion of the first rotary step, relay G is released due to the circuit of its right-hand winding being opened at the 550 rotary magnet springs R, whereupon relay KR then operates and at armature kr3 closes a point in the circuit of the switching relays HA and HB.

If now the first set of contacts engaged by 600 the wipers are not those marked, wipers P1

and P2 will both encounter earth thereby maintaining a short-circuit on relays HA and HB and completing the following circuits for the pre-operation of relay G; earth at wiper P1, armature ha6, springs R, bank contact 70 and wiper 15, armature k3, right-hand winding of relay G to battery, and similarly earth at wiper P2, armature hb6, wiper 17 and bank contact, armature fr3, armature e4, left-hand winding of relay G to battery. 75 Consequently relay G again completes the circuit to the rotary magnet RM and the wipers are advanced onto the next set of bank contacts. This cycle of operations continues until the marked line which is indicated by the absence of earth potential is reached, and assuming that wiper P1 encounters the marked line, relay G cannot again operate since there is now no circuit for its right-hand winding. Moreover the short-circuit across the winding of relay HA is now removed and this relay thereupon operates over the circuit: earth at armature kr3, 80 wiper 14 and bank contact, springs RN, winding of relay HA, armature hb3, springs R, 85 bank contact and wiper 15, armature k3, right-hand winding of relay G to battery. Relay HA upon operating completes a locking circuit for itself as follows: earth fed over conductor P', armature ha2, winding 90 of relay HA, armature hb3, armature ha1, winding of vertical magnet VM to battery. Furthermore at armature ha3 a point is opened in the circuit of relay HB, at armatures ha4 and ha5 the negative and positive 95 leads from the group selector are extended through to the wipers of the finder and relay FR is released, and finally at armature ha6 earth over conductor P' is connected through to the test wiper of the finder in order to 100 mark the calling line busy and to effect the operation of the cut-off relay in the calling subscriber's line circuit which thereupon clears the calling line of its normal battery and earth connections.

Relay FR in releasing causes relays K and KR to release and the wipers of the finder allotter FA are accordingly advanced onto the next set of bank contacts. Upon the release of the connection earth is removed 105 from conductor P' thereby causing relay HA to release, while at the same instant a circuit is completed to the finder switch release magnet from earth over conductor Z and the switch is thus restored to normal in the well-known manner.

What we claim as new and desire to secure by Letters Patent is:

1. In a telephone system, a group of finders each having primary and secondary hunting movements, a stepping relay common to all said finders, means for temporarily associating said relay with any one of said finders in response to a call, and circuits controlled 120 by said relay for operating the associated

finder in its primary and secondary hunting movements to find the calling line.

2. In a telephone system, a group of finders each having primary and secondary hunting movements, a stepping relay common to all said finders, means for temporarily associating said relay with any one of said finders in response to a call, circuits controlled by said relay for operating the associated finder in its primary and secondary hunting movements to find the calling line, means for stopping the primary movement in response to the finder encountering one potential and for initiating the secondary movement, and means for stopping the secondary movement in response to the finder encountering a different potential.

3. In a telephone system, a group of finders each having primary and secondary hunting movements, a stepping relay common to all said finders, means for temporarily associating said relay with any one of said finders in response to a call, circuits controlled by said relay for operating the associated finder in its primary and secondary hunting movements to find the calling line, test wipers in said finder, and means for simultaneously testing over a pair of said wipers for a calling line during the secondary hunting movement.

4. In a telephone system, a calling line, a group of finders each having primary and secondary hunting movements to find said line, a switching relay in each finder for completing the talking circuit to the calling line, a stepping relay common to said finders, an allotting switch, wipers in said switch for allotting said finders for use in turn, means for operating said wipers to connect said relay with one of said finders in response to a call, circuits controlled by said relay over said wipers for operating the connected finder in its primary and secondary hunting movements to find the calling line, a circuit including one of said wipers for initially energizing the switching relay of the connected finder responsive to the finder finding the calling line, and another circuit for holding said switching relay energized completed responsive to its energization.

5. In a telephone system, a group of finders each having primary and secondary hunting movements, a stepping relay common to all said finders, a rotary switch common to said finders, wipers in said switch for allotting said finders for use in turn, means for operating the wipers of said switch to connect said relay with one of said finders in response to a call, and circuits controlled by said relay over said wipers for operating the connected finder in its primary and secondary hunting movements to find the calling line.

6. In a telephone system, a group of finders each having primary and secondary hunting

movements, a stepping relay common to all said finders, two windings on said relay, a rotary switch common to said finders, wipers in said switch for allotting said finders for use in turn, means for operating the wipers of said switch to connect said relay with one of said finders in response to a call, a circuit for each winding of said relay, means for energizing said relay only when both circuits to both windings are completed, and circuits controlled by said relay over said wipers for operating the connected finder in its primary and secondary hunting movements to find the calling line.

7. In a telephone system, a group of finders having primary and secondary hunting movements, a change-over relay common to all said finders for stopping the primary hunting movement and for initiating the secondary hunting movement, a stepping relay common to all said finders for operating the finders in their hunting movements, an allotting switch, wipers in said switch for allotting any one of said finders for use in response to a call, and a circuit completed responsive thereto for energizing said relays.

8. In a telephone system, a group of finders having primary and secondary hunting movements, a primary test wiper for each finder, a primary magnet in each finder for operating the finder in its primary hunting movement, a secondary magnet in each finder for operating the finder in its secondary hunting movement, an operating circuit for said magnets, a stepping relay common to all said finders, a change-over relay common to all said finders, means for connecting said relays and circuit with one of said finders and for energizing said relays, means for intermittently operating said stepping relay to intermittently open and close said operating circuit to operate the magnets of said finder, means responsive to the test wiper of said finder encountering a predetermined potential for deenergizing said changeover relay, and means responsive to the deenergization of said changeover relay for transferring said operating circuit from the primary magnet to the secondary magnet of said finder.

9. In a telephone system, a group of finders having primary and secondary hunting movements, a stepping relay common to all said finders, a changeover relay common to all said finders, a rotary switch, wipers in said switch for allotting said finders for use in turn, means for operating the wipers of said switch to connect said relays with one of said finders in response to a call, a circuit completed responsive thereto for energizing said relays, an operating circuit for operating said finders in their primary and secondary hunting movements, means for intermittently operating said stepping relay to in-

- 5 intermittently open and close said operating circuit, and means for deenergizing said changeover relay to transfer the operating circuit to stop the primary hunting movement and initiate the primary hunting operation.
10. In a telephone system, a group of finders having primary and secondary hunting movements, a primary test wiper for each 10 finder, a changeover relay common to all said finders, means for energizing said relay to initiate the primary hunting movement of an idle one of said finders, means responsive to the primary test wiper of said finder 15 encountering a predetermined potential for stopping the primary hunting movement of said finder and for deenergizing said relay, and means responsive to the deenergization of said relay for initiating the secondary 20 hunting movement of said finder.
11. In a telephone system, a calling line, a group of finders having access to said line, a primary magnet in each finder for operating the finder in a primary hunting movement, 25 a secondary magnet in each finder for operating the finder in a secondary hunting operation, an operating circuit for operating the magnets of said finders, a stepping relay common to said finders, means for connecting 30 said relay with one of said finders, means for intermittently operating said stepping relay to intermittently open and close said operating circuit, and a change-over relay common to said finders for transferring said 35 operating circuit from the primary magnet to the secondary magnet of the connected finder.
12. In a telephone system, a calling line, a group of finders having access to said line, 40 a primary magnet in each finder for operating the finder in a primary movement, a secondary magnet in each finder for operating the finder in a secondary movement, a stepping relay common to all said finders 45 for controlling said magnets, means for temporarily associating said relay with any one of said finders in response to a call on said line, and means controlled by said relay for operating the primary magnet and then the 50 secondary magnet of the associated finder to find the calling line.
13. In a telephone system, a calling line, a plurality of finders having access to said line, a primary magnet in each finder for operating 55 the finder in a primary hunting movement, a secondary magnet in each finder for operating the finder in a secondary hunting movement, an operating circuit for operating the magnets of said finders, a change-over 60 relay common to said finders, an allotting switch common to said finders, wipers in said switch for allotting said finders for use in turn, means for operating the wipers of said switch to connect said relay with one of said 65 finders and to complete said circuit in re- sponse to a call, and means controlled by said relay for transferring said operating circuit from the primary magnet to the secondary magnet of the connected finder.
14. In a telephone system, a calling line, a plurality of finders having access to said line, a primary magnet in each finder for operating the finder in a primary hunting movement, a secondary magnet in each finder for operating the finder in a secondary hunting 75 movement, an operating circuit for operating the magnets of said finders, a change-over relay common to said finders, means for temporarily associating said relay with any one of said finders to complete said circuit in re- 80 sponse to a call, and means controlled by said relay for transferring said operating circuit from the primary magnet to the secondary magnet of the associated finder.
15. In a telephone system, a group of finders having primary and secondary hunting movements, a primary test wiper in each finder, a change-over relay common to said finders for changing the operation of said 85 finders from their primary to their secondary hunting movements, a stepping relay common to said finders for operating the finders in their hunting movements, an allotting switch, wipers in said switch for allotting any one of said finders for use in response to a call, a cir- 90 circuit completed responsive thereto for energizing said relays in a series circuit including wipers on said switch, means responsive to the test wiper of said finder encountering a pre- 95 determined potential during the primary movement of said finder for completing a holding circuit for said stepping relay, and means responsive thereto for holding the circuit of said change-over relay open to deener- 100 gize said change-over relay.
16. In a telephone system, a calling line, a finder having primary and secondary hunting movements to find said line when calling, a primary test wiper in said finder, an operating circuit for operating said finder in its two hunting movements, a stepping relay for intermittently closing and opening said circuit, a change-over relay for transferring said circuit to change the operation of said 110 finder from its primary to its secondary hunting movement, means for energizing said re- 115 lays responsive to a call to close said operating circuit to operate said finder in its primary movement, means responsive to said wiper encountering a predetermined potential for deenergizing said change-over relay, circuits for temporarily maintaining said stepping relay energized before and after the deenergization of said change-over relay, and means responsive to the deenergization of 120 said change-over relay for completing said operating circuit maintained by said stepping relay to initiate the operation of said finder in its secondary movement.
17. In a telephone system, a calling line, a 125 130

plurality of finders having access to said line, a primary magnet in each finder for operating the finder in a primary hunting movement, a secondary magnet in each finder for operating the finder in a secondary hunting movement, an allotting switch common to said finders, wipers in said switch for allotting said finders for use in turn, means responsive to a call for operating said wipers to connect 10 said switch with one of said finders, a circuit including one of said finders, a circuit including one of said wipers for operating the primary magnet of the connected finder, means responsive to said connection for completing 15 said circuit to operate said primary magnet, a switching relay in said finder for completing the talking circuit to the calling line, a circuit including said one wiper for energizing said relay, and means responsive to said 20 finder finding the calling line for completing said last circuit to energize said switching relay.

In testimony whereof we affix our signatures.
